DESIGN FOR A BAG

Joseph C. Walters, Philadelphia, Pa., assignor to
John Hoffmann & Sons Company, Milwaukee,
Wis., a corporation of Wisconsin

Application November 19, 1938, Serial No. 81,230

Term of patent 7 years

To all whom it may concern:

Be it known that I, Joseph C. Walters, a citizen of the United States and a resident of Philadelphia, Pennsylvania, have invented a new, original, and ornamental Design for a Bag, of which the following is a specification, reference being had to the accompanying drawing, forming part thereof, in which:—

Fig. 2 is a rear view; and

Fig. 3 is a side view, the opposite side being identical therewith.

I claim:—

The ornamental design for a bag, substantially as shown and described.

JOSEPH C. WALTERS.
